UNITED STATES PATENT OFFICE.

ADOLF VOGELSANG, OF DUSSELDORF, GERMANY.

RAILROAD-RAIL-FASTENING DEVICE.

SPECIFICATION forming part of Letters Patent No. 724,064, dated March 31, 1903.

Application filed November 15, 1902. Serial No. 131,592. (No model.)

To all whom it may concern:

Be it known that I, ADOLF VOGELSANG, a subject of the King of Prussia, Emperor of Germany, residing at Dusseldorf, in the Kingdom of Prussia, German Empire, have invented certain new and useful Improvements in Railroad-Rail-Fastening Devices, of which the following is a specification.

My invention relates to an improved fastening for holding down railway-rails on their sleepers, more particularly sleepers consisting of cement blocks, without the employment of bolts, spikes, or the like; and the objects of my improvement are, first, to provide a cheap construction enabling the track to be readily laid with the greatest security and admitting of repairs being undertaken and new rails substituted for worn-out ones without any difficulties and without injuring or damaging thereby any of the parts constituting the novel device; second, to obtain and insure at the same time a rigid connection between the two rails forming the track. I attain these objects by the mechanism or devices illustrated in the accompanying drawings, in which—

Figure 1 is a cross-section of a rail secured to the supporting-block by my new device, taken on the line A A of Fig. 2, which is a plan view of Fig. 1, the head of the rail being removed. Fig. 3 is a cross-section corresponding to Fig. 1, drawn to a smaller scale, showing the whole breadth of the track. Figs. 4 to 8 are detail views to be hereinafter referred to. Fig. 9 is a perspective view showing a modified construction of the holdown iron or plate which I employ. Fig. 10 is a cross-section of a rail secured by the aid of the iron shown in Fig. 9.

In the construction shown in the drawings the foot of the rail *a* on the one side of the web is held down by a hook *d* on a band *c*, which surrounds the cement block *b*, here forming the sleeper. The band *c*, with hook *d*, is shown separately in Fig. 4. On the opposite side of the web the rail-foot is held to the block by the hooks *e*, formed on the U-shaped iron or plate *f*. (Shown separately in Fig. 5.) The plate *f* is inserted below the foot of the rail from the outside and is connected to the corresponding plate *f* of the opposite rail *g* of the track (see Fig. 3) by means of an

iron bar *h* of inverted-U or channel section. A portion of the bar *h* is shown in perspective in Fig. 6. The connection is such that the vertical downwardly bent or hooked end *i* of the bar *h* passes through a slot in the plate *f* and bears laterally against the block *b*.

In order that the tie-bar may secure the rails with thorough rigidity, an angle-iron *k* (shown in perspective in Fig. 7) is inserted between the tongue or hook *i* and the body of the bar *h* and secured by a pin *l* (shown in perspective in Fig. 8) to the flanges or side walls of the bar *h*.

As already mentioned, the construction above described is only one of the many forms of the invention which may be adopted. Thus without departing from the feature of the invention the hook *d* instead of being formed on a closed band *c* may be provided on a band having open ends capable of being connected together by bolts or otherwise, or it may be arranged on a base-plate or the like. The band form is more especially adapted for those cases in which instead of wooden sleepers blocks of cement or the like are employed.

The other members of the device—such as the U-shaped plate *f*, the tie-bar *h*, and the stiffeners *k*—likewise may be greatly varied in form without departing thereby from the essential features of my invention. Thus Figs. 9 and 10 illustrate a modified form of the plate *f*, according to which the hooks *e* of the said plate, onto the end or bridge-piece of which is hung the hooked end *i* of the tie-bar *h*, are prolonged upward so as to reach the head of the rail. They thus form a support, counteracting the tendency of the tires of the wheels to force the head of the rail outward. The foot of the rail *a* is in this case held down on the inside by a hook *d* and on the outside by the hooks or claws *e* of the U-shaped plate shown in Fig. 9, over the bridge-piece *f* of which the hook *i* of the tie-bar *h* grips. The hooks *e* run upwardly and laterally, and their ends butt against the under side of the head of the rail *a*. They thus steady the latter by presenting a support thereto and form a means which effectually opposes the forces tending to drive the head of the rail out of the line of the track.

What I claim as my invention, and desire to secure by Letters Patent, is—

1. The combination, in a railway-rail-fastening device, of longitudinal or block sleepers having hooks or claws *d*, attached thereto for holding down the inside foot of the rail, plates *f*, inserted between the foot of the rail and the said sleeper and having hooks or claws *e*, to hold down the outside foot of the rail and a tie-bar *h*, having a vertical tongue *i*, at each end to be passed through a slot in the said plates arranged below the rails forming the track so as to rigidly connect said rails.

2. The combination, in a railway-rail-fastening device, of longitudinal or block sleepers having bands embracing said sleepers and provided with hooks or claws *d*, for holding down the inside foot of the rail, plates *f*, inserted between the foot of the rail and the said sleeper and having hooks or claws *e*, to hold down the outside foot of the rail and a tie-bar *h*, having a vertical tongue *i*, at each end to be passed through a slot in the said plates arranged below the rails forming the track so as to rigidly connect said rails, essentially as set forth.

3. In a railway-rail-fastening device, the combination of longitudinal or block sleepers having hooks or claws *d*, attached thereto for holding down the inside foot of the rail, **U**-shaped claw-plates *f*, inserted between the foot of the rail and the said sleeper and having hooks or claws *e*, to hold down the outside foot of the rail and a tie-bar *h*, having a vertical tongue *i*, at each end to be passed through a slot in the said plates arranged below the rails forming the track so as to rigidly connect said rails, substantially as described.

4. In a railway-fastening device, the combination of longitudinal or block sleepers having bands embracing said sleepers and provided with hooks or claws *d*, for holding down the inside foot of the rail, plates *f*, inserted between the foot of the rail and the said sleeper and having hooks or claws *e*, to hold down

the outside foot of the rail and a tie-bar *h*, having a vertical tongue *i*, at each end to be passed through a slot in the said plates arranged below the rails forming the track so as to rigidly connect said rails, substantially as shown.

5. The tie-bar *h*, having a vertical tongue *i*, at each end of such length as to widely bear against the opposite surfaces of the sleepers to afford a rigid structure.

6. In combination, a tie-bar *h* having an inverted-**U** section and a tongue *i*, and a stiffener *k* adapted to be inserted between the tongue *i* and the side walls of the bar, substantially as described.

7. In combination, a stiffener *k* having a vertical cross portion and two angular flanges projecting therefrom, a tie-bar having a tongue *i* and vertical longitudinal flanges, and a pin for connecting the stiffener and tie-bar, said pin passing through holes in the flanges of said parts, substantially as described.

8. The combination, in a railway-rail-fastening device, of longitudinal or block sleepers having hooks or claws *d*, attached thereto for holding down the inside foot of the rail, plates *f*, inserted between the foot of the rail and the said sleeper and having hooks or claws *e*, to hold down the outside foot of the rail, said hooks or claws extending laterally upward so as to support the head of the rail, and a tie-bar *h*, having a vertical tongue *i*, at each end to be passed through a slot in the said plates arranged below the rails forming the track so as to rigidly connect said rails, essentially as set forth.

In testimony whereof I have signed my name to this specification in the presence of two subscribing witnesses.

ADOLF VOGELSANG.

Witnesses:

PETER LIEBER,
WILLIAM ESSENWEIN.
